UNITED STATES PATENT OFFICE.

FREDERICK A. SMITH, OF PHILADELPHIA, PENNSYLVANIA.

LOUD SPEAKER.

Application filed February 11, 1924. Serial No. 691,871.

To all whom it may concern:

Be it known that I, FREDERICK A. SMITH, a citizen of the United States, residing at Philadelphia, in the county of Philadelphia and State of Pennsylvania, have invented 5 certain new and useful Improvements in Loud Speakers, of which the following is a specification.

My invention relates to loud speakers, 10 particularly for radio receiving apparatus, and it relates more particularly to an improved form of device adapted to amplify and project the sound waves generated by an electric telephonic receiving unit.

15 The principal object of my invention is to provide a simple and relatively inexpensive apparatus of novel form for amplifying and projecting the sound waves generated by the receiving unit of a wireless telephone apparatus. A further object thereof is to provide such a device which will project the sound waves uniformly in all directions; and a still further object thereof is to provide an apparatus for the 20 purpose mentioned which will be relatively small and compact, which will present a pleasing appearance, and which will not be subject to destruction by being knocked over, as frequently occurs with the use of the 25 unwieldy types of loud speakers at present in common use.

The nature and characteristic features of 30 my invention will be more readily understood from the following description, taken 35 in connection with the accompanying drawings forming part hereof, in which:

Figure 1 is a vertical central section of 40 a loud speaker, for radio receiving apparatus, embodying the main features of my present invention;

Fig. 2 is a top or plan view thereof, partly broken away; and

Fig. 3 is a side elevation thereof.

Referring to the drawings, in the particular embodiment of my invention therein shown, 5 is a base member having an external skirt portion 6 and an internal inverted bell shaped portion 7, in the lowermost central portion of which is an upwardly projecting teat 8. An upper member 9 is supported above the base member 5, preferably by means of tubular columns 10. The upper member 9 is also of an inverted bell shape, but the central portion thereof is somewhat smaller in diameter 55 than the corresponding part of the bell

shaped portion 7 of the base member 5, and is also somewhat more elongated in vertical dimension, so as to provide an annular flaring space 11 between the surfaces 60 of the bell shaped portion of the base member 5 and the upper member 9.

The lowermost portion of the upper member 9 is recessed as at 12, and in this recess, directly above the teat 8 of the lower member, there is mounted an electrically actuated telephonic receiving unit 13, which may be of any preferred construction, such as are commonly used in loud speakers of radio receiving apparatus. The lead-in wires 14 for the receiving unit 13 pass from said unit through the interior of the upper member 9, thence preferably extending through one of the tubular columns 10 to the interior of the base member 5, and thence 75 through an aperture 15 provided with an insulating bushing 15 to the exterior thereof. The upper and lower members, 9 and 5 respectively, are preferably made of hollow aluminum castings, and the top of the 80 upper member 9 is preferably closed by means of a plate 16, which is seated therein in a complementary recess.

The sound waves which are generated by the electrical receiving unit 13 are first projected toward the teat 8, and thence through the annular flaring space between the surface of the upper member 9 and the inner surface of the bell shaped portion 7 of the base member, finally being deflected by the 85 flaring portion of the upper member 9 in a horizontal direction, the space 11 between said surfaces constituting, in effect, an annular horn in which the sound waves are amplified before being projected outward. 95

It will be seen that there is thus provided a simple and compact, yet efficient, form of loud speaker which will serve to amplify the sound waves and project them uniformly in all directions, and that the structure is so arranged as to present a pleasing appearance, and is unlikely to be upset, and thereby damaged, as frequently occurs in the use of the topheavy and ungainly loud speakers at present in common use. 105

Having thus described the nature and characteristic features of my invention, what I claim as new and desire to secure by Letters Patent is:

1. A loud speaker comprising a member 114 having an internal flaring bell-shaped surface, another member having a flaring bell-

shaped surface and having its central portion smaller in diameter and more elongated in vertical dimension than the bell-shaped surface of the first named member and extending into the interior of the first named member so as to provide an annular flaring space between the surfaces of said members, and a telephonic receiving unit mounted at the inner central portion of one of said members.

2. A loud speaker comprising a member having an internal flaring bell-shaped surface, another member having a flaring bell-shaped surface and having its central portion smaller in diameter and more elongated in vertical dimension than the bell-shaped surface of the first named member and extending into the interior of the first named member so as to provide an annular flaring space between the surfaces of said members, one of said surfaces having a centrally disposed projecting teat, and a telephonic receiving unit mounted at the inner central portion of one of said members oppositely disposed with respect to said projecting teat.

3. A loud speaker comprising a member having an internal flaring bell-shaped surface, another member having a flaring bell-shaped surface and having its central portion smaller in diameter and more elongated in vertical dimension than the bell-shaped surface of the first named member and extending into the interior of the first named member so as to provide an annular flaring space between the surfaces of said members, a telephonic receiving unit mounted at the inner central portion of one of said members, and means for holding said members in spaced relationship comprising columns extending between the flaring portions of said members.

4. A loud speaker comprising a hollow

base member having an inner inverted bell shaped surface, an upper hollow member held in fixed relationship with respect to the lower member, said upper member having an inverted bell shaped surface so disposed with respect to the inner surface of the base member as to provide an annular flaring space therebetween, a telephonic receiving unit mounted in the lower portion of one of said members, the means for holding said base member and upper member in spaced relationship comprising tubular columns, and the connection wires for said telephonic receiving unit passing through one of said tubular columns and the hollow interiors of said base and upper members.

5. A loud speaker comprising a hollow base member having an inner inverted bell shaped surface with a centrally disposed upwardly extending teat, an upper member held in fixed relationship with respect to the lower member, said upper member having an inverted bell shaped surface so disposed with respect to the inner surface of the base member as to provide an annular flaring space therebetween, a telephonic receiving unit mounted in the lower portion of the upper member above the projecting teat of the inner surface of the lower member, the means for holding said base member and upper member in spaced relationship comprising tubular columns, and the connection wires for said telephonic receiving unit passing therefrom through the hollow interior of the upper member, thence through one of said tubular columns, and thence through the hollow interior of the base member and through an aperture therein to the exterior.

In testimony whereof, I have hereunto signed my name.

FREDERICK A. SMITH.
